UNITED STATES PATENT OFFICE.

EUGENE F. NISSEN, OF ALAMEDA, CALIFORNIA.

SAFETY-CONTAINER.

1,340,555.

Specification of Letters Patent.

Patented May 18, 1920.

Application filed May 19, 1919. Serial No. 293,001.

To all whom it may concern:

Be it known that I, EUGENE F. NISSEN, a citizen of the United States, residing at Alameda, in the county of Alameda and 5 State of California, have invented new and useful Improvements in Safety-Containers, of which the following is a specification.

This invention relates to a safety container and particularly pertains to envelopes 10 and structures of like character.

The present invention is particularly concerned with an envelop adapted to be used by fiscal agents in sending money and valuable documents by mail or express. Heretofore it has been practically impossible to design an envelop which could not be steamed open and thereafter re-sealed and it is the principal object of the present invention to provide an envelop which is so 20 folded and secured in its folded position that access cannot be obtained to the contents of the envelop without leaving some mark or without in some way mutilating the envelop.

25 The present invention contemplates the use of an envelop formed of heavy paper or fabric which is so folded that all of the walls will be double and will be gummed and stitched in such a manner as to prevent 30 entering the envelop.

The invention is illustrated by way of example in the accompanying drawings in which:

Figure 1 is a view in plan showing the 35 envelop blank and further indicating the gummed portion thereof.

Fig. 2 is a view in plan showing the envelop blank as partially folded.

Fig. 3 is a view showing the envelop blank 40 with its large side-flap folded.

Fig. 4 is a view showing the envelop blank with the two side-flaps in their folded and over-lapping position.

Fig. 5 is a view showing the completely 45 formed envelop.

Fig. 6 is an enlarged view showing the envelop after it has been stitched.

Fig. 7 is a view in elevation showing the folded and sealed envelop.

50 Fig. 8 is a view in transverse section through the envelop on the lines 8—8 of Fig. 7.

Fig. 9 is a view in longitudinal section through the envelop as seen on the lines 55 9—9.

In the drawings, 10 indicates a rectangular front field. At one side of this field is formed a rectangular side-flap 11, agreeing in dimensions with the front field. At the opposite side of the front field is formed a short rectangular flap 12. This flap is of the same width as the front field but of a length considerably shorter. A back panel 13 is formed as a continuation of one end of the front panel and agrees with the dimensions thereof. Directly upon the opposite side of the front panel 10 is a sealing flap 14. This flap may be of any desired dimension but is preferably of the same width as the front panel. Formed as a continuation of the side-flap 11 is a safety flap 15. This flap is of the same dimensions as the panel 11 and extends alongside of the back panel 13 when the blank is unfolded. A secondary sealing flap 16 is formed along 75 one edge of the safety flap 15 for a purpose which will be hereinafter set forth.

In forming the envelop the sealing flap 14 is gummed as indicated at 17. The short side-panel 12 is gummed as indicated at 18 80 and the back panel is gummed along its opposite side as indicated at 19 and 20. The secondary sealing flap is gummed on both sides along its opposite edges as indicated at 21 and upon its back as indicated at 22 85 in Fig. 2. In forming the envelop the safety flap 15 is folded along the score mark *a* and is adapted to fold over to coincide with the side flap 11. When in this position the secondary sealing flap 16 will extend upwardly 90 above the edge of the flap 11 as indicated in Fig. 2. The safety and side flap 11 and 15 are then folded over on the score mark *b* to conform to the front panel 10. After this has been done the short panel 12 is 95 folded over the end of the side-panel 11 and sealed along the gummed surface 18. The two side-flaps which has thus been sealed together are then covered and completely concealed by the back-flap 13 as indicated in 100 Fig. 5. The two side-flaps and the back flap are then fastened together by a plurality of mechanical fasteners 24 which will be positioned near the marginal edges of the back flap and also at points intermediate. 105 It will thus be seen that the flaps of the envelop will be folded so that the auxiliary flap 16 will be secured across the inner face of the sealing flap 14 by means of the gummed surface 22 and that the side-flaps 110

will be securely covered by the back flap which is sealed thereto along the gummed surfaces 19 and 20 and further secured by means of the mechanical fasteners.

5 When the envelop has been thus formed it is stitched as indicated at 25 in Figs. 6 and 7. This stitching extends from one corner of the auxiliary seal flap along the end of the envelop across the bottom of the envelop and up the other side to the opposite corner. The stitching will pass through the back flap, the auxiliary flap 16 and the two side-flaps. The ends of the thread are intended to be folded over and to be sealed 15 down between the back panel and the sealing flap when the envelop is closed.

It will be evident from an examination of the drawings and a consideration of the foregoing specification that an envelop will 20 be provided which is practically secure against any sort of manipulation of the flap or panels whereby access to the interior of the envelop could be obtained, it being further noted that due to the fact that all of 25 the exposed edges of the finished envelop are stitched and that the ends of the thread are secured in a sealed position beneath the flap 17, that any effort to remove this stitching or to substitute other stitching therefor, 30 would be useless.

Having thus described my invention, what

I claim and desire to secure by Letters Patent is:

An envelop composed of a front panel, opposite side flaps borne thereby, a back panel connected to the bottom of the front panel, a sealing flap connected to the top of the front panel, a safety flap connected to the bottom of one of the side flaps, and a secondary sealing flap connected to the bottom of the safety flap, the safety flap being folded onto said side flap and the secondary sealing flap being gummed onto the main sealing flap, the back panel being superimposed upon the safety and other side flap, and both sealing flaps being gummed onto the back panel, and stitching extending around the bottom and sides of the back panel and through the latter and through the secondary sealing flap and the two side flaps, the ends of the thread extending out from the secondary sealing flap and being folded to lie between the latter and the back panel.

In testimony whereof I have hereunto set 55 my hand in the presence of two subscribing witnesses.

EUGENE F. NISSEN.
